ELECTRON DISCHARGE DEVICE

Hans Gerhard Lubszynski, Hillingdon, and
George Stanley Percival Freeman, Chiswick,
London, England, assignors to Electric & Mu-
sical Industries Limited, Hayes, Middlesex,
England, a company of Great Britain

Application January 15, 1937, Serial No. 120,642
In Great Britain January 15, 1936

8 Claims. (Cl. 250—165)

This invention relates to electron discharge de-
vices having photo-electrically-active electrodes.

In the manufacture of electron discharge de-
vices comprising an electrode bearing a deposit
5 of photo-electrically-active material, such as
caesium, it is often desirable to prevent or to re-
tard the access of this material to other elements
within the envelope of the electron discharge de-
vice.

10 The chief object of the present invention is to
provide improved methods of manufacturing such
devices whereby the difficulties usually encoun-
tered in preventing the deposit of the photo-elect-
rically-active material upon certain electrodes
15 or supports where such deposit is not desired are
reduced or avoided, and improved designs of
electron discharge devices for use in such
methods.

According to one feature of the present inven-
20 tion, electron discharge devices are manufactured
with a view to avoiding or reducing the above-
mentioned difficulties by inserting within the en-
velope of the device, in addition to the electrode
intended to be sensitised with photo-electrically-
25 active material, an element or material capable
of absorbing said photo-electrically-active ma-
terial, shielding said element or material during
the photo-sensitising operation and thereafter
displacing the shield to expose the whole or a part
30 of said element or material.

Another feature of the invention is the manu-
facture of an electron discharge device in which
excess photo-electrically-active material is ab-
sorbed, and this feature of the invention com-
35 prises the steps of inserting in the envelope of the
device an element having on one of its surfaces a
material capable of absorbing said photo-sensi-
tive material, shielding said surface, introducing
said photo-electrically-active material and there-
40 after exposing said surface to absorb excess
photo-electrically-active material.

In order that the said invention may be clearly
understood and readily carried into effect, the
same will now be more fully described with refer-
45 ence to the accompanying diagrammatic drawing
in which:—

Figure 1 illustrates a light-transformer, the
fluorescent screen of which is adapted to be
shielded during photo-sensitisation,

50 Figure 2 illustrates a conventional form of
cathode ray tube in which excess photo-electric-
ally-active material is absorbed after photo-sen-
sitisation,

Figure 3 is an end elevation looking towards the
55 right-hand end of Figure 2,

Figure 4 is a view similar to Figure 3, but show-
ing a modified and preferred form for absorbing
excess photo-electrically-active material,

Figure 5 shows a further form of the invention,
and

Figure 6 shows an enlarged detail of a portion
of Figures 2 and 5.

Referring to Figure 1 of the drawings, this
illustrates a light-transformer, comprising an elec-
50 trated envelope 5 having at one end an elec-
trode 6 which is adapted to be photo-sensitised
and, at the other end, a fluorescent screen 7.
Prior to photo-sensitisation of the electrode 6, a
shield 8 is placed in contact with the fluorescent
55 screen 7 so as to prevent the photo-electrically-
active material, such as caesium, from becoming
deposited on the screen 7. The shield 8 is made
of mica or of other suitable material and consists
of a flat plate of such a shape that it is capable
60 of covering the surface of the fluorescent screen.
In the example shown, the shield 8 is hinged at
the lower end of the screen 7 as indicated at 9,
and such hinge may be carried by a support 7'
for the screen 7. The shield 8 serves to prevent
65 photo-electrically-active material becoming de-
posited on the fluorescent screen 7 whilst the
screen 6 is being sensitised and after the envelope
has been finally evacuated the shield 8 is dis-
placed to the position indicated in dotted lines
70 so that it will not interfere with the normal opera-
tion of the device. The shield 8 may be moved to
the dotted line position shown by manipulation of
the tube or, alternatively, a clip of magnetic ma-
terial, such as iron, may be provided on the mica
75 plate so that the shield can be manipulated from
the exterior of the envelope by a suitable magnet.
In some cases, instead of the shield 8 being
hinged, it may be normally unconnected with
the screen 7 or its support, the envelope being
80 maintained in a suitable position during sensitisa-
tion so that the shield is maintained in the re-
quired position and after the sensitising opera-
tion, the envelope is manipulated to displace the
shield so as to expose the screen 7 for normal
85 operation.

The device shown in Figure 1 is, as aforesaid,
a light-transformer, but the invention is not
limited in its application to light-transformers,
since it can also be applied to similar devices,
such as one in which the screen 7 is replaced by
90 a mosaic screen.

Figures 2 and 3 of the drawing illustrate the
application of the invention to the case in which
it is desired to absorb excess-photo-electrically-
active material after the sensitising operation.

The invention is shown as applied to a cathode ray tube comprising a bulbous envelope 10 having a mosaic screen 11 in the bulbous portion which is adapted to be sensitised with photo-electrically-active material. The mosaic screen in the example shown, comprises a mica disc having on one face a large number of separate oxidised silver elements and on the other face a continuous silver layer which forms a signal plate. The mosaic screen 11 is held in position in the envelope 10 by a support plate 12 consisting of a disc of mica extending nearly to the walls of the bulb and supported therein by radial springs 13 at three points as shown in Figure 3. A semi-circular flap of mica or other suitable material 14 is hingedly attached at its straight edge to the back of the support 12 in such a manner that, when it pivots about its hinge, its curved edge sweeps adjacent to the wall of the bulb. The support plate may be unsilvered, and the mica flap provided with an oxidised silver coating on the side adjacent the support plate. Alternatively, the support plate may have an oxidised silver coating on its back over at least the area of its surface adapted to be covered by the flap, and the flap in this case may or may not be provided with an oxidised silver coating on the side adapted to contact with the silvered part of the support plate. Preferably however the whole of the back of the support plate and both sides of the flap are coated with oxidised silver aggregated into minute sub-divisions. The curved edge of the flap may carry a soft iron clip 15 which enables the flap to be swung round by means of a magnet outside the bulb. During photo-sensitisation of the mosaic screen, the flap lies in contact with the surface of the support plate 12 so that at least a part of the silver coating on one of these members is shielded. After the mosaic screen has been photo-sensitised, the flap is displaced to the dotted line position shown in Figure 2, so as to expose the silver previously shielded, which is now capable of absorbing excess caesium. The flap 14 may be held during normal operation of the tube in the dotted line position shown in Figure 2, so that the surface which absorbs excess photo-electrically-active material is normally exposed by causing the flap 14 to jam between the support plate 12 and the wall of the envelope 10.

The arrangement described in connection with Figures 2 and 3 may be modified as shown in Figure 4 by substituting for the flap a pair of discs 16 and 17 of mica or other suitable material having approximately the diameter of the support plate 12 and loosely riveted together at their centres at 18. The disc 17 is riveted to the back of the support plate, for example, at the points where the three supporting springs 13 are attached. The other disc 16 which lies on the back of the disc 17, is provided with sector-shaped slots 19 uniformly spaced and exposing nearly one-half of the surface of the under disc 17, which surface is coated with oxidised silver, which may be aggregated. The outer surface of the slotted disc may also be coated with oxidised silver, which may be aggregated. A soft iron clip 20 is riveted to the edge of the slotted disc and enables this disc to be rotated about the central rivet 18 by means of a magnet, so as to expose, when desired, a fresh surface of silver through the slots.

The arrangement last described has the following advantages. As it operates in a plane parallel to that of the support plate, it is easy

to move; it does not tend to buckle the assembly and it effectively prevents diffusion of caesium between the slotted disc and the under disc. Furthermore, the under disc serves to stiffen the mosaic screen as a whole, and the weight is taken directly by the support springs. 5

In some cases the material on the electrode or other part to be shielded may be impaired due to direct contact of the flap 8 or 14, and to avoid their direct contact the periphery of the flap may be provided with an annular rim which maintains the shield out of contact with the electrode or part to be shielded, the flap and rim effectively obscuring the electrode until the flap is displaced as above described. 10

In another form of the invention as shown in Figure 5, for the purpose of absorbing excess photo-electrically-active material, an absorbent, such as cuprous oxide, may be contained in a cup-shaped receptacle 25 suitably positioned within the tube on a support such as 12, the absorbent being normally shielded by the provision of a cap 26 fitting over or into the cup-shaped receptacle. When it is desired to expose the absorbent, the cap may be removed by manipulation of the device, or by magnetic means cooperating with a piece of magnetic material 27. 15

We claim:—

1. An electron discharge device comprising an envelope, a support member within said envelope, a surface to be photo-electrically sensitized, a shield member, means securing said surface to one side of said support, means pivotally securing said shield to the other side of said support, a part of said other side of the support being coated with material capable of absorbing photo-sensitizing material, said shield being adapted to cover the absorbing material during sensitization of the surface and to be pivoted to expose the absorbing material after sensitization. 30

2. An electron discharge device comprising an envelope, a support member within said envelope, a portion of one side of which is coated with material capable of absorbing photo-sensitizing material, a surface to be photo-sensitized, a shield member, means pivotally securing said shield to the coated side of said support, and means securing said surface to the other side of said support, said shield being adapted to cover the absorbing material or to expose the same. 40

3. An electron discharge device comprising an envelope, a support member within said envelope, a surface to be photo-sensitized, a shield member, means securing said surface to one side of said support, the other side of the support having a portion thereof coated with a material capable of absorbing photo-sensitizing material, and means pivotally securing the shield to said other side of the support whereby the absorbing material may be exposed or covered by the shield by manipulation of the device. 50

4. An electron discharge device comprising an envelope, a support member within said envelope, a surface to be photo-sensitized, a shield member, means securing said surface to one side of said support, the other side of the support having a portion thereof coated with a material capable of absorbing photo-sensitizing material, means pivotally securing the shield to said other side of the support, and magnetic means attached to 65 said shield whereby the shield may be pivoted to expose or cover the absorbing material. 70

5. An electron discharge device comprising an envelope, a support member within said envelope, a surface to be photo-electrically sensitized, a 75

shield member, means securing said surface to one side of said support, means hingedly securing said shield to the other side of said support, the side portion of said shield next to the said other side of the support being coated with material capable of absorbing photo-sensitizing material, said shield being adapted to lie in contact with said support to conceal the absorbing material or to be hinged from said support to expose the absorbing material.

6. An electron discharge device comprising an envelope, a support member within said envelope, a surface to be photo-sensitized, means securing said surface to one side of said support, a shield having one side coated with material capable of absorbing photo-sensitizing material, and means hingedly securing said shield to the other side of said support with the coated side adjacent thereto whereby the absorbing material may be concealed or exposed.

7. An electron discharge device comprising an envelope, a support member within said envelope, a surface to be photo-sensitized, means securing

said surface to one side of said support, a shield having one side coated with material capable of absorbing photo-sensitizing material, means hingedly securing said shield to the other side of said support with the coated side adjacent thereto, and magnetic means attached to said shield whereby the shield may be hinged to conceal or expose the absorbing material.

8. An electron discharge tube comprising an envelope, a support member within said envelope, a surface to be photo-sensitized, means securing said surface to one side of said support, a circular shield having one or more sector openings therein, corresponding sector shaped portions of the other side of said support being coated with a material capable of absorbing photo-sensitizing material, and means pivotally securing the shield to said other side of the support for angular movement whereby the absorbing material may be covered or exposed.
